US0D1071222S

(12) **United States Design Patent** (10) Patent No.: **US D1,071,222 S**
(45) Date of Patent: ** Apr. 15, 2025

(54) **DENTAL CT SCANNER**

(71) Applicant: **YOFO (HEFEI) MEDICAL TECHNOLOGY CO., LTD.**, Hefei (CN)

(72) Inventors: **Lei Zhu**, Anhui (CN); **Tian Li**, Anhui (CN); **Ran Xu**, Anhui (CN); **Wenrui Yu**, Anhui (CN); **Zhe Liu**, Anhui (CN); **Junqi Ma**, Anhui (CN); **Xianjin Guan**, Anhui (CN)

(**) Term: **15 Years**

(21) Appl. No.: **35/521,068**

(22) Filed: **Mar. 23, 2024**

(80) **Hague Agreement Data**

Int. Filing Date: **Mar. 23, 2024**

Int. Reg. No.: **DM/237105**

Int. Reg. Date: **Mar. 23, 2024**

Int. Reg. Pub. Date: **May 31, 2024**

(30) **Foreign Application Priority Data**

Feb. 6, 2024 (CN) 202430081847.1

(51) **LOC (15) Cl.** **24-01**

(52) **U.S. Cl.**

USPC **D24/158**

CLAIM

The ornamental design for a dental CT scanner as shown and described.

DESCRIPTION

1. Dental CT scanner

1.1 : Perspective

1.2 : Perspective

1.3 : Perspective

1.4 : Front

1.5 : Back

1.6 : Top

1.7 : Bottom

1.8 : Left

1.9 : Right

The parts shown in broken lines are for illustrative purposes only and form no parts of the claimed design.

1 Claim, 9 Drawing Sheets
